UNITED STATES PATENT OFFICE.

RICHARD S. WARING, OF PITTSBURG, PENNSYLVANIA.

MANDREL FOR CABLE-PRESSES.

SPECIFICATION forming part of Letters Patent No. 294,542, dated March 4, 1884.

Application filed August 9, 1883. (No model.)

To all whom it may concern:

Be it known that I, RICHARD S. WARING, a citizen of the United States, residing at Pittsburgh, county of Allegheny, State of Pennsylvania, have invented or discovered a new and useful Improvement in Mandrels for Cable-Presses; and I do hereby declare the following to be a full, clear, concise, and exact description thereof, reference being had to the accompanying drawings, making a part of this specification, in which—like letters indicating like parts—

Figure 1 is a view in side elevation of my improved mandrel. Fig. 2 is an end view, looking downward upon the nipples or point. Fig. 3 is a longitudinal sectional view, the plane of section being indicated by the line xx , Fig. 2. Figs. 4 and 5 are transverse sectional views taken in the planes of the lines yy and zz , respectively; and Figs. 6 and 7 are perspective and sectional views, respectively, of the cable made by means of my improved mandrel.

My invention relates to the manufacture of an electric cable such as represented at R, Figs. 6 and 7, having a group of insulated conducting-wires, r , inclosed each in its appropriate passage formed in the common body, of lead or equivalent soft-metal covering, r' , which covering also incloses a series of hard-metal wires, r'' , designed to afford tensile strength and prevent injury to the conducting-wires by abrasion or wearing away of the lead covering. The only material difficulty encountered in the manufacture of a cable of this construction by means heretofore employed—namely, a lead-press—is due principally to lack of provision therein for supplying lead to the inner spaces between wires, and at the same time secure the desired proximity of wires and prevent lateral displacement of them by pressure of lead thereon.

My present invention is especially designed to meet these and similar requirements in manufacture; and, in general terms, it consists of a mandrel having passages therethrough both for the insulated conducting-wires and also for the strengthening-wires, such passages terminating at the point of the mandrel in tubular nipples, the nipples for strengthening-wires being arranged at intervals around the nipples for conducting-wires, with grooves

in the outer surface of the mandrel for directing flow of lead to different parts of the spaces surrounding the nipples, as hereinafter more fully described and claimed.

55

In the drawings, A represents a tapering body, of iron, steel, or other suitable metal, having a threaded socket, a , in its base end, adapted to screw onto the threaded end of tubular core-bar B. A chambered recess, A' , 60 in or below the base of the socket, registers with the tubular passage of the core-bar, and affords a common opening for leading in the several wires to be contained in the cable. From the base of recess A' are drilled separate passages a' , leading through the body A, and emerging at the point or tapered end in the form of distinct nipples or tubular extensions e . The inner or central nipples, e , (three being shown in the present instance,) 70 are designed for passing therethrough the insulated conducting-wires, and they occupy positions in close proximity at equal intervals from the common center. The outer or surrounding nipples, e' , (six in number, as shown,) 75 are made at equal intervals around the inner set of nipples, e , and are designed for passing therethrough the strengthening-wires of the cable. These nipples may be made integral with the body portion of the mandrel by turning or otherwise forming them thereon; or, if preferred, they may be made separate from and be screwed into tapped holes in the end of the body portion, or be otherwise rigidly secured thereto. I prefer to make them on or 80 as integral parts of the body, because they can be formed in this way of less metal and within less space. In order to make provision for passing a supply of lead into the inner spaces between nipples, grooves c are cut longitudinally in the tapered sides of the mandrel, which extend downward to the point between the nipples e . In depth these grooves extend within the circle of nipples e' , and by preference to or within the circle of inner nipples, e . 85 90 95

It will be observed that the number of grooves c and of nipples e' is double the number of nipples e , and that the nipples e' occur at equal intervals on either side of radial lines 100 produced from the nipples e . This provision is made with reference to directing streams of

lead through the grooves e , both upon the extreme outer surface of nipples e and also upon their adjacent sides, through grooves directed to or into the spaces between nipples e . Lead 5 directed in this manner will pass readily into the narrow central spaces between nipples e , and will insure adhesive union with the lead directed upon the outer side of these nipples, and thus passing off from the nipple-points 10 will envelop the insulated wires with continuous unbroken walls of lead covering, which, however, will be thin or light between wires.

Substantially the same uniformity of lead-supply is thus afforded within and around the 15 central portion of the cable as though the nipples e' and the strengthening-wires were not present, and in doing this I avoid injurious side pressure of lead upon the outer nipples, e' , and also upon the wires passed therethrough.

20 This is an important feature of construction, as it enables me to make the nipples comparatively light, so as to secure compactness without injurious weakening of them.

It will also be observed that lead, following 25 the depths of grooves e , will have motion or direction of flow substantially in the longitudinal direction of the nipples, making but comparatively little lateral spread necessary to unite the lead around the nipples when the 30 same are reached. This is also a material advantage in preventing breakage of nipples by side pressure thereon, and it affords almost complete relief from side pressure, not only upon the strengthening-wires, as above explained, but also upon the insulated conducting-wires. Side pressure, if it existed, would be a fatal obstacle to close grouping of wires, owing to the tendency of such pressure to flex 35 or bend the wires out of their true or desired 40 relationship or positions, and the construction and arrangement of grooves and nipples by which such difficulty is obviated is an important feature of advantage and improvement with reference to close grouping of wires to 45 secure economy in the use of lead and lightness of product.

In illustrating the principles of my invention I have shown provision for three conducting-wires, six strengthening-wires, and a corresponding number of grooves. I do not wish, 50

however, to limit my invention to these or any specific numbers, as the same may be increased or diminished, as required, with reference to the desired size or capacity of cable; but in making such changes in the number of wires I 55 prefer to retain substantially the same relationships of numbers and positions of nipples and grooves, because better results are secured thereby in covering the wires.

I make no claim herein to the cable shown 60 and described, as the same, in so far as it may contain patentable invention, will be included in the subject-matter of a separate application for patent.

I have also embraced in other applications 65 mandrels having side grooves extending to the point between groups of nipples, and therefore I do not claim herein such features alone considered, my present invention having additional reference to the special arrangement 70 and relationship of the nipples to the grooves, as herein set forth.

I claim herein as my invention—

1. A mandrel for a cable-press, having separate passages therethrough for insulated conducting and for strengthening wires, such passages terminating at the point in tubular nipples, the nipples for conducting-wires being grouped at the center, and the nipples for strengthening-wires surrounding such central 80 group, with grooves in the surface of the mandrel extending to the point between the nipples for strengthening-wires, substantially as set forth.

2. The mandrel A, having wire-passages 85 therethrough, terminating at the point in separate nipples, three of such nipples e being near the center and surrounded by double the number of nipples e' , arranged in circular order, with grooves e in the surface of the mandrel, extending in depth between the outer nipples, e' , to the inner group of nipples, e , substantially as and for the purposes set forth.

In testimony whereof I have hereunto set my hand.

RICHARD S. WARING.
